C. C. HAMILL

AMALGAMATING MEANS

Filed July 12, 1924

INVENTOR
CHARLES. C. HAMILL.
BY,

Graham Harris

ATTORNEYS.

UNITED STATES PATENT OFFICE.

CHARLES C. HAMILL, OF RANDSBURG, CALIFORNIA.

AMALGAMATING MEANS.

Application filed July 12, 1924. Serial No. 725,721.

To all whom it may concern:

Be it known that I, CHARLES C. HAMILL, a citizen of the United States, residing at Randsburg, in the county of Kern, State of California, have invented a new and useful 5 Amalgamating Means, of which the following is a specification.

My present invention is an amalgamation plate and a process of preparing and using 10 the same in the recovery of precious metals; and it is an especial object of this invention to provide for use an improved amalgamation plate presenting a comparatively rough surface, suitable to the retention of fine particles of a precious metal passing thereover 15 in suspension.

Extensive losses have heretofore resulted 20 from the use of comparatively smooth amalgamation plates, whose surfaces afford no adequate lodgement for the retention of fine 25 particles, such particles having been permitted to float off and to be lost with the gangue; and it is accordingly an object of this invention to provide the surface of an 30 amalgamation plate with an uneven surface, such as may be formed by the association of suitable solid particles or undissolved residues of particles of a metal such as silver, with sufficient "quick" to form a waxy but

rough coating on a base plate.

The mentioned base plate may be of copper, or the like; and in a preferred embodiment of my invention, I may prepare a mixture of, for example, silver filings and mercury of a consistency suitable for application by a brush; and I may spread the resultant amalgam mixture on the mentioned base plate duly silver coated, to a thickness such as to provide minute pockets or depressions between the undissolved residues of silver particles, in which pockets even minute particles of gold may find lodgement for a period sufficient to permit their amalgamation; and the mentioned amalgamation 40 of gold particles, these particles being of various sizes, may permit subsequent application of mercury in such manner as to build up a plate covered by the mentioned amalgam mixture and particles of precious metals 45 to any desired thickness. The resultant mixture may finally be separated from the base plate and the constituent metals may be separated and completely recovered, in any usual or preferred manner, as by retorting.

Other objects of my invention will appear 55 from the following description of an advantageous embodiment thereof, taken in connection with the appended claims and the accompanying drawings, in which

The figure is a perspective representation 60 of a corner or fragment of an amalgamation plate suitable for use in the practice of my invention.

Referring to the details of that specific 65 embodiment of my invention chosen for purposes of illustration, a base plate 11, of copper or other suitable material, this plate being of any preferred size such as five by ten feet, is adapted to be used on an agitating table (not shown) of any usual or preferred 70 design, and said plate may be coated with an amalgam mixture, of somewhat waxy consistency, comprised of quicksilver and subdivided solid materials, such as residues of silver filings, capable of partial amalgamation therewith. This amalgam mixture may be prepared either by initially coating the silvered plate 11 with amalgam and sprinkling silver filings, or the like thereon, or by stirring, as in a mixing bowl, a suitable quantity 75 of such filings, or their equivalent, into mercury in such quantity as to produce the desired waxy consistency, while leaving the mentioned filings, or their equivalent, largely 80 undissolved and in suspension therein. In either of the cases referred to, the amalgam 85 mixture may be spread in a comparatively thin layer, and preferably by means of a brush or broom, over the entire surface of the plate 11, or over any desired part thereof, in such manner as to produce a roughened surface by the projection of the separate undissolved residues 12 of individual filings, coated with amalgam, above the average 90 level produced by the application of said mixture, the interstices being thus adapted to permit a lodgement of particles of gold, or the like, for a period sufficient to assure 95 the amalgamation thereof. The plate 11 amalgamated as described may be mounted 100 upon a table (not shown) at any suitable inclination and agitated in any preferred way, and a suitably subdivided ore, or a black sand, or the like, may be fed thereto over the edge of a distributing board, or the like, in 105 any usual or preferred manner. The deposit may be built up to any desired depth, as by the occasional adding of suitable quan-

ties of quicksilver; and the entire resultant coating mixture may finally be separated and its constituents may be recovered and refined in any usual or preferred manner, as 5 by retorting.

Although I have herein described a single complete embodiment of my invention, it will be understood that various features thereof might be independently employed 10 and also that various modifications might be made by those skilled in the art, without the slightest departure from the spirit and scope

of my invention, as the same is indicated above and in the following claim.

I claim as my invention:

15 A means for the recovery of gold by amalgamation comprising a base plate covered with a mixture of mercury and silver filings producing a rough surface.

In testimony whereof, I have hereunto set 20 my hand at Los Angeles, California, this 5th day of July, 1924.

CHARLES C. HAMILL.
